UNITED STATES PATENT OFFICE.

HENRY J. GILBERT, OF SAGINAW, MICHIGAN.

FOLDING TABLE.

Application filed September 24, 1925. Serial No. 58,229.

My invention relates to folding tables, and is more particularly adapted to collapsible ironing boards or tables of the type in which the board is provided with collapsible legs which fold flat against the board, so that the device occupies little space when not extended for use, and in collapsed form is convenient for shipment or storage. The object of my invention is to provide a board 10 of such character having a collapsible supporting structure which shall be strong, stable and mechanically efficient, and also simple in construction and operation, to the end that it may be economically manufactured, and be convenient in use. These desirable results I attain by the novel construction and arrangement of the members of the supporting structure hereinafter described in detail, the essential elements of my invention being more particularly pointed out in the appended claims defining my invention.

In the accompanying drawings I have illustrated my invention both in a preferred form and in a modified form of embodiment. Figure 1 of the drawings shows a side view of the preferred form with the legs in extended position, showing also in dotted lines the relative positions of the folding members when partly collapsed, it being understood, however, that in folding the table it may most conveniently be manipulated by supporting the table on what will be termed its rear end while the legs are being folded; Fig. 2 is a bottom plan view of the folded table; Fig. 3 is a detail of a fastener on the under side of the table for securing the end of a supporting strut; Fig. 4 is a longitudinal vertical section of the same, employing the term "vertical" (as well as other expressions hereinafter employed to indicate position) with reference to the position of the parts when the leg structure is extended and the table set up ready for use; Fig. 5 is a detail showing the construction of a pivoting bracket secured to the cross member of the rear legs, the associated parts being shown in folded position, as in Fig. 2; Fig. 6 is a section of the same on the line 6—6 of Fig. 5; Fig. 7 is a detail side view of the same parts in extended position, corresponding to the position shown in Fig. 1; Fig. 8 is a side view of the modified form of my invention, corresponding to Fig. 1; Fig. 9 is a bottom plan view of such modification; Figs. 10 and 11 are details of the modified form of a construction corresponding re-

spectively to Figs. 5 and 6; Fig. 12 is a detail of a pivotal connection of the front legs and supporting strut, and Fig. 13 is an enlarged detail view of a bearing plate and stop at the upper end of the front leg of the table.

The same reference characters indicate the same parts in all the figures of the drawing.

Describing first the preferred form of my invention illustrated in Figs. 1 to 7, inclusive, the ironing board 1 is provided on its under side near its rear end with a transverse metal bar 2, bent at right angles at its ends to form pivoting lugs 2^a—2^a. The two rear legs 3—3, which are rigidly secured together by a cross bar 4 are in the present instance provided with bearing plates 3^a having each a short bottom flange engaging a transverse kerf in the inner side face of the leg, and the branches 5—5 of the front leg are equipped with bearing plates 5^a—5^a, similarly flanged and arranged, and each having also an inclined end flange 5^b which in the extended position of the leg structure brings up against the rear edge of the corresponding pivoting lug 2^a, the legs being pivoted to such lugs by headed pivots 6—6 which provide bearings for the rear and front legs. Centrally of the cross-bar 4 is secured a bracket piece 7 formed with an upwardly extending flange 8, which is formed with forwardly extending pivoting lugs 9—9 and rearwardly inclined stop lugs 9^a—9^a. To stiffen and strengthen the rear leg structure I provide obliquely disposed braces 10—10 secured to opposite ends of the bracket piece 7 and the legs 3—3.

To support the front end of the table I employ a floating strut 11 extending between the bracket piece 7 and a rotatable flat locking button 12 carried by a plate 13 secured to the under face of the board centrally near its forward end, the front end of the strut being equipped with a slotted metal bearing piece 14 arranged to engage the locking button, which may be rotated to lock or to release the forward end of the strut. The strut is pivotally connected with the branches of the front leg by means of a cross rod 15 extending between them, and is also pivotally connected to the upper and forward ends of a pair of links 16—16 which are pivoted at their lower ends to the pivoting lugs 9—9 of the bracket piece 7 beforementioned. For the purpose of center-

ing the strut 11 between the branches of the front leg while permitting free pivotal rotation of the parts, the cross rod 15 is formed with annular grooves at its center and near its ends which are engaged by a central retaining pin 15^a driven into engagement therewith through the strut, and a pair of end retaining pins in the form of screws 15^b seated in the branches of the leg.

- 10 In extended position the strut 11 and links 16—16 extend parallel with each other and in effect form a composite truss element extending between the cross rod 15 and pivoting lugs 9—9, the parts of this truss element forming a toggle joint at the forward end of the links. To put these elements under compression and put the front and rear legs under tension, holding them against separation when the strut and links are in alignment, I provide a tension rod 17 which is pivoted between the branches of the front leg adjacent its foot and which at the rear passes through a slot in the bracket piece 7 and is formed with a stop head 18, in the present instance a loop, arranged to bring up against the rear side of said bracket piece and take up all looseness in the pivoting of the parts when the leg structure is fully extended.
- 30 The lower end of the strut is arranged to bear against the stop lugs 9^a—9^a when the leg structure is extended and guard against any excessive strain on the pivotal connections of the links 16—16.

- 35 To accommodate the tension rod 17 in folded position it will be noted that the cross bar of the rear legs is formed with a groove 19.

It is manifest that the extended leg structure, considered alone, is a rigid stable structure in which all loose motion of the parts is taken up, and that a weight upon the ironing board will exert a compressive stress on the strut member and a tensile strain on the tension rod which will all the more strongly increase this interaction and relationship of the parts.

The modified form of my invention illustrated in Figs. 8 to 11 inclusive operates in the same manner as the preferred form already described, but differs in the form of the bracket piece and connecting link pivoted to the bracket piece and supporting strut. In this modified form the bracket piece, marked 20, is formed with up-turned portions bent to form hinge rolls 21 which are connected by a pintle 22 with a hinge roll formed at the lower end of a single flat link 23 which is hinged at its upper end to a plate 24 fast to the under side of the strut 11. The rear side of the bracket piece is formed with an inclined stop flange 20^a against which the lower end of the supporting strut abuts when the leg structure is extended, the rear end of the tension rod 17 being formed

with a crosshead 17^a which in such extended position lies within the angle between the rolls and body of the bracket piece.

The upper ends of the branches of the front leg may be cut away at an angle and extended rearwardly to form stops 5^c—5^c, for the purpose of preventing excess unfolding movement of the legs beyond their normal extended position, and the front and rear legs may be directly pivoted by means of pivot bolts 6^a—6^a to the pivoting lugs 2^a, as shown in Figs. 8 and 9 illustrating the modified form of my invention.

For convenience in securing a cloth cover to the ironing board I have provided screw eyes 25 seated in the board through orifices in the bar 2. In setting up the board it will be found convenient to rest the rear end of the folded board upon the floor, then extend the front and rear legs together until the front leg is arrested by the stop flanges 5^b—5^b of the bearing plates 5^a—5^a, then further extend the rear legs and bring the strut 11 into parallelism with the links to form a rigid leg structure, and then lock the upper end of the strut to the board through the locking button 12. In folding the board, the strut may be disengaged from the locking button, and the toggle joint between the strut and links broken, after which the folding of the rear legs will automatically also fold the front leg.

I claim:

1. In a folding ironing table, an ironing board, a pair of rigidly connected rear legs pivoted to said board adjacent its rear end, a forwardly inclined front leg also pivoted to said board adjacent its rear end, a supporting strut pivoted intermediate its length to said front leg at an intermediate point thereof, said strut being arranged to be detachably connected at its upper end to the forward portion of said board and to bear at its lower end against said connected rear legs and constituting a compression member intermediate said board and rear legs, a link element pivoted to said connected rear legs and also pivoted to said strut at a point between said rear legs and front leg to form a toggle, and a tension rod arranged to connect the lower portions of said front leg and rear legs.

2. In a folding ironing table, an ironing board, a pair of rigidly connected rear legs pivoted to said board adjacent its rear end, a bracket piece carried by said rear legs and supported centrally therebetween, a forwardly inclined front leg also pivoted to said board adjacent its rear end, a supporting strut pivoted intermediate its length to said front leg at an intermediate point thereof, said strut being arranged to be detachably connected at its upper end to the forward portion of said board, a link element pivoted to said bracket piece and also pivoted to said

strut between said bracket piece and front leg to form a toggle, the rear end of said strut being arranged to abut against said bracket piece, and a tension rod arranged to connect said front leg and said bracket piece.

3. In a folding ironing table, an ironing board, a pair of rigidly connected rear legs pivoted to said board adjacent its rear end, a bracket piece carried by said rear legs and supported centrally therebetween, a forwardly inclined front leg also pivoted to said board adjacent its rear end, a supporting strut pivoted intermediate its length to said front leg at an intermediate point thereof, said strut being arranged to be detachably connected at its upper end to the forward portion of said board, a link element pivoted to said bracket piece and also pivoted to said strut between said bracket piece and front leg to form a toggle, the rear end of said strut being arranged to abut against said bracket piece, and a tension rod pivotally connected with said front leg near its foot and passing loosely through said bracket piece, the rear end of said rod being equipped with a head arranged to engage said bracket piece.

4. A folding table according to claim 1 in which said link element consists of a pair of link members on opposite sides of the supporting strut and the lower end of the strut member therebetween is arranged to bear against said connected rear legs.

5. A folding table according to claim 2 in which said bracket piece is formed with pivoting portions arranged to pivotally engage the link element and an inclined stop face arranged to abut against the end of the supporting strut.

6. A folding table according to claim 2 in which said link element consists of a pair of link members on opposite sides of the supporting strut and said bracket piece is formed with a pair of pivoting ears arranged to provide pivot bearings for said links and

with a slot between said ears to receive the tension rod and with inclined stop flanges.

7. In a folding ironing table, an ironing board, a pair of rigidly connected rear legs pivoted adjacent opposite sides of the board near its rear end, a forwardly inclined front leg comprising branches united at the foot and having their tops pivoted adjacent and in axial alignment with the pivotal axis of the rear legs, said branches being connected by a cross rod, a supporting strut pivoted at a point intermediate its length on said cross rod, said cross rod being formed with an annular central groove and annular end grooves and said strut and branches of the front leg being connected to said cross rod by retaining pins, the upper end of said strut being arranged to engage said board and its lower end arranged to engage said connected rear leg, and a tension rod connected to said front leg near its foot and connected to said connected rear legs adjacent the lower end of said strut.

8. In a folding ironing table, an ironing board equipped with pivoting lugs, a pair of rigidly connected rear legs pivoted to said board adjacent its rear end, a forwardly inclined front leg consisting of branches and having at least one of said branches equipped with a bearing plate formed with a stop flange arranged to bring up against the corresponding pivoting lug, a supporting strut pivoted intermediate its length to said front leg at an intermediate point thereof, said strut at its upper end being arranged to detachably engage the forward portion of the board, a link element pivoted to said connected rear legs and also pivoted to said strut between said rear legs and said front leg to form a toggle, and a tension rod pivoted to said front leg near its foot and arranged to engage said connected rear legs adjacent the pivotal connection of the link element therewith.

HENRY J. GILBERT.
